CAR VESTIBULE DIAPHRAGM

Filed May 9, 1930

UNITED STATES PATENT OFFICE

HARRY U. MORTON, OF CHICAGO, ILLINOIS, ASSIGNOR TO MORTON MANUFACTURING COMPANY, OF CHICAGO, ILLINOIS, A CORPORATION OF ILLINOIS

CAR VESTIBULE DIAPHRAGM

Application filed May 9, 1930. Serial No. 450,902.

This invention relates to diaphragms for railway car vestibules. Such diaphragms are usually constructed of flexible material such as canvas, rubberized fabric, or other suitable material.

During travel of a train, the cars sway and lurch relatively and where the diaphragms are of a length to contact with the foot plates the material of the diaphragms soon becomes worn and frayed by the frictional contact and abrasion thereof against the foot plates. Where the diaphragms are vertically sectional, such wear will require frequent repair or replacement of the lower sections.

An important object of the invention is to provide wearing strips or cuffs at the lower ends of the diaphragm which strips are preferably of resilient material such as sponge rubber which will not become frizzled or frayed under frictional contact with the foot plate and which will yieldingly and snugly engage with the foot plate at all times so as to also form an effective weather strip or barrier between the diaphragm ends and the foot plates.

Another important object is to provide lower vertical sections for the diaphragm which are comparatively narrow vertically and which at their lower ends have secured thereto the protecting and weathering strips above referred to. These lower sections or cuff structures are stitched or otherwise secured to the upper sections so that they may be readily removed and replaced should they become worn out.

The various features of my invention are incorporated in the structure shown on the drawing, in which drawing:

Figure 1 is a front elevation of a diaphragm structure,

Figure 2 is an enlarged vertical section through one leg of the diaphragm structure,

Figure 3 is an enlarged section on plane III—III of Figure 2,

Figure 4 is an enlarged side elevation of a section of the wearing and protecting cuff structure, and

Figure 5 is a section on plane V—V of Figure 4.

The diaphragm shown comprises the top of

arch section 1 and the vertical or side sections 2 and 3. The vertical sections or lengths each comprise folds 4 of suitable fabric such as canvas, such folds at their adjacent edges being secured together as by stitching or riveting, but preferably by means of a metal clamp 5 and rivets 6.

The top or arch section 1 is constructed of similar folds and on the inner sides of the ends of this arch section are arranged strips of material 7 secured by folding over the upper edges of the strip and sewing or riveting such edges to the arch section. This arrangement provides pockets 8 into which the upper ends of the folds 4 of the side sections may extend to be secured as by means of stitching.

At the lower ends of the side sections or legs 2 and 3 are provided comparatively very short cuff structures 9 and 10. As shown in Figure 3, each cuff structure is formed from a strip of material such as canvas, the strip being bent or folded at the middle as indicated at 11, the two sections 12 and 13 forming outer loops or folds and the end sections 14 and 15 of the strip being folded back against the outer folds 12 and 13, and terminating adjacent to the bend 11. The outer and inner folds 12 and 14 and the outer and inner folds 13 and 15 respectively receive between them the folds 4 of the long leg sections 2 and 3 and these sections and the cuff structures are secured together as by stitching as indicated at 16, Figures 4 and 5. At the bottom of each cuff structure and between the outer and inner folds thereof I insert an abutment and weathering strip 17 for engaging against the foot plate over which the diaphragm is secured in the vestibule passageway between cars. This strip is preferably of material which will not fray or frizzle under rubbing and frictional engagement with the foot plate and I have found that material such as sponge rubber is very desirable and efficient. The abutment and weathering strip is secured between the folds of the cuff structure fabric as by means of stitching 18. The material of the folds 4 may extend into the cuff structure down to the strip 17 so that the cuff structure will be stiffened and strengthened and better en-

100

abled to withstand the wear and tear to which it is subjected.

The strips 17 being of resilient material such as sponge rubber will, by their resiliency and elasticity, be at all times kept in intimate contact with the foot plate during relative movement of the cars of a train and will keep out wind and weather. The strips may wear eventually but they will not frazzle or fray and become unsightly. After a strip has become worn away so that its weathering efficiency will be impaired a new strip may be inserted in the cuff structure or the cuff structure may be entirely detached and replaced by a new cuff structure.

Referring to Figure 2, the metal clamps 5 which secure together the adjacent edges of the folds 4 of the sections 2 and 3, may be extended down as far as the weathering strips 17 and receive the folds 11 of the cuff structure fabric. The structures will thus be further stiffened and strengthened.

I have shown and described a practical and efficient embodiment of my invention but I do not desire to be limited thereto as changes and modifications may be made without departing from the scope and principles of the invention.

I claim as follows:

- 30 1. The combination with a diaphragm of the class described, of floor engaging strips extending along the lower edges thereof and formed of sponge rubber.
- 35 2. The combination with a diaphragm of the class described, of floor engaging weathering strips extending from the lower edges thereof and formed of material having the characteristics of sponge rubber.
- 40 3. A diaphragm structure of the class described comprising vertical legs formed of folds of material, a cuff structure for the lower end of each leg, each cuff structure comprising a strip of fabric folded to surround and receive the end of the leg folds, and a floor engaging strip received between the folds of the cuff fabric and extending downwardly therefrom and being formed of material having the characteristics of soft rubber.
- 45 4. A diaphragm of the class described comprising vertical legs formed of folds of material, a cuff structure for each leg comprising a strip of fabric having folds for receiving the ends of the leg folds and having a floor engaging strip of pliable resilient material secured between its folds and extending downwardly therefrom for engagement with the floor.
- 50 5. The combination with a diaphragm of the class described, of cuff structures receiving the lower ends of the vertical legs of the diaphragm, and wearing and weathering strips extending beyond the lower ends of said cuffs and formed of sponge rubber.
- 55 6. In a railway car vestibule diaphragm of

the accordion type, vertically extending legs of flexible sheet material and feet of softer and more flexible sheet material attached to the lower ends of the legs as downward continuations of the latter.

7. In a railway car vestibule diaphragm of the accordion type, vertically extending legs made of heavy fabric, and feet of sheet material attached to the lower ends of the legs as downward continuations of the latter, said feet being more flexible than the legs, whereby to yield readily to deformation and thereby prevent transmission of the major deforming stresses to the legs.

8. In a railway car vestibule diaphragm of the accordion type, vertically extending legs made of heavy fabric, and feet of sheet material attached to the lower ends of the legs as downward continuations of the latter, said feet being more susceptible to deformation than the legs, whereby to absorb the deforming stresses received from the floor plates of the vestibule.

In testimony whereof I have hereunto subscribed my name at Chicago, Cook County, Illinois.

HARRY U. MORTON.
